Primary Examiner — S. Bryan Reinholdt, Jr.

(57) **CLAIM**

The ornamental design for an outdoor planter, as shown and described.

DESCRIPTION

FIG. 1 is a front and top perspective view of an outdoor planter, showing my new design;

FIG. 2 is a front and bottom perspective view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portion, labeled '9' of FIG. 1; and,

FIG. 10 is an enlarged view of the portion, labeled '10' of FIG. 1.

The broken lines depict portions of the outdoor planter in which the design is embodied that form no part of the claimed design.

The dot-dash-dot broken lines depict the boundaries of the enlargements that form no part of the claimed design.

1 Claim, 10 Drawing Sheets(56)
